[57] CLAIM

The ornamental design for a ceiling fan supporting bracket with an adornment, as shown and described.

DESCRIPTION

FIG. 1 is a front-right-bottom perspective view of a ceiling fan supporting bracket with an adornment, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a front right bottom perspective view thereof, wherein the broken lines are shown for illustrative purposes only and form no part of the claimed design.
